(54) **HAMMER, ARM FORGE**

(76) Inventor: **James Sharp**

James Sharp of Spruce Creek, Pennsylvania
Letters Patent

The Schedule referred to in these Letters Patent and making part of the same containing a description in the words of the said James Sharp himself of his improvement in the Forge Hammer Arm.

To all to whom these Presents shall come, Be it known that I James Sharp, of Spruce Creek, in the County of Huntingdon, and State of Pennsylvania, have invented a new and useful improvement in the Forge Hammer Arm; and that the following is a full and exact description of the construction and operation of said machine as invented, or improved by me.

The shaft by which the arm is to be set in motion is to be supported on each end, by an upright on which the arm plays. At one end of said shaft is to be affixed the wheel or pulley, by which the motion is to be given, either by water, steam, or other means. At the other end is to be a cylinder of wood, of size proportioned to the water wheel, and should one be used.

In this cylinder is to be inserted an arm of a peculiar construction to be described hereafter. This arm in the revolution of the cylinder is to raise the lever of the Hammer, thereby giving motion to the Hammer in its rise and fall.

The above mentioned arm or projection from the lever is called a flapet arm, and is to be made of cast iron of a square form let into the cylinder to sufficient depth to give it hold, and to project far enough beyond, to raise the lever the desired height.

The lower part of the under side, on the length of the arm opposite to that, which comes in contact with the hammer lever, is hollowed into a semicircular groove extending as far up as the arm as it is to be fitted into the cylinder. In this hollow is to be fitted a wooden key projecting as far above the face of the arm, as will be necessary to give it strength and elasticity, tapering to a wedge shape towards the bottom. This forms the principle for

ture of my improvement, as the wooden key or wedge of this semi circular shape allows of a spring in the play of the semi, thereby securing its durability and lightness. The upper portion of the remaining side is to be rounded at the edge, and a portion of the metal depressed with, in order to decrease its weight in the upper part. On the side of said arm, either on the right or left, is to be left a small projection of the metal of the depth of the insertion in the cylinder for the purpose of drawing the same in its socket under a band or hoop passing round the cylinder, and projecting over the mortise in the cylinder a space equal to the thickness of said projection of metal. A wedge is to be driven on the opposite side made of wood and having, the projection on the arm to the place under the hoop.

Another hoop, or clasp, passes over the wedge and secured also, this arm may be used either to the right or the left.

On the lower part of the Hammer lever is to be secured a plate of iron, on that part which comes in contact with the iron arm, thereby preventing its firm from wear.

My claim is, for the taffrail arm as above described with its said appendages and arrangement.

In testimony that the above specification of my improvement is true and correct. I have hereunto set my hand the fifth day of June in the year of our Lord Eight hundred and forty four.

Witnessed
Henry Stone
William Hobbs.

James Sharp
